UNITED STATES PATENT OFFICE.

HERMAN C. KRASE, OF CHICAGO, ILLINOIS.

LOCK FOR BASCULE-BRIDGES.

1,042,238.

Specification of Letters Patent. Patented Oct. 22, 1912.

Application filed March 14, 1912. Serial No. 683,730.

To all whom it may concern:

Be it known that I, HERMAN C. KRASE, a citizen of the United States, and a resident of Chicago, in the county of Cook and State 5 of Illinois, have invented a new and Improved Lock for Bascule-Bridges, of which the following is a specification.

My invention relates to improvements in means for locking or holding bascule bridges, 10 or structures of a similar type, in position, and it consists in the combinations, constructions and arrangements herein described and claimed. A requisite of a lock for such a structure is that it shall firmly 15 hold some portion of the bridge, in such a way that the strains of the counterweight will be taken up, and yet the lock must be of such a construction that it may be readily withdrawn so as to permit the swinging of 20 the bridge.

My main object therefore is to provide a device in which the strains are taken up by the lock and one which is easily manipulated so as to permit the bridge to open.

A further object of my invention is to provide locking means of great power for forcing the heel of the counterweight tightly against the bumping block so as to prevent any movement of the bridge while in use.

A further object of my invention is to provide a simple device for locking a bascule or lift bridge which has few parts and which is therefore not liable to get out of order, these parts being such that they may be 35 easily replaced when worn.

Other objects and advantages will appear in the following specification, and the novel features of the device will be particularly pointed out in the appended claims.

My invention is illustrated in the accompanying drawings forming part of this application in which similar reference characters indicate like parts in the several views, and in which,

Figure 1 is a side view of my invention as applied to a bascule bridge; Fig. 2 is a detail view of my improved lock showing its different positions with respect to the bridge; Fig. 3 is a sectional view along the line 3—3 of Fig. 1; Fig. 4 is a view of a modified form of locking device; Fig. 5 is a sectional view along the line 5—5 of Fig. 4; and Fig. 6 is a perspective view showing a portion of the central part of one 50 of the locked members.

In order to give a thorough understanding of the invention, I have shown certain

parts of a bascule bridge and will briefly refer to these parts since they constitute no part of my invention except in so far as 60 they coöperate with my locking means.

Referring now to Fig. 1, A represents in general a bascule bridge having a rocker or rolling segment B which rolls on a track C, on the pier P. At W is shown a counterweight which is provided with an extension w at its rear end, arranged to engage a bumper Y. In order for the bridge to swing, the roadway is divided at R, the portion r being on the bridge proper and the portion 70 r' being on the approach to the bridge. I have indicated diagrammatically the operating pinion at O, but the means for operating the bridge, as stated before, forms no part of my invention. Projecting rearwardly 75 from the extension w of the counterweight W is a heel H with which my improved locking member is arranged to coöperate.

While I have shown one counterweight and one locking member in Fig. 1, it will 80 be understood that there are two, one on each side of the roadway, as shown in the modified form in Fig. 4. A description of one of these locking members will suffice, however, since they are precisely the same. 85

Referring now to Figs. 2 and 3, it will be seen that attached to the anchor column S is a bracket T to which is pivotally secured one arm v of the locking member V. The arm v has one end formed in the manner shown in Fig. 6. It will be seen from this figure that there is a semi-cylindrical bearing v' on one-half of the end and a cylindrical bearing v² on the other half. The abutting end of the other member or 95 arm vx is similarly arranged so that when these members are pivoted together by means of a pin, such as that shown at E in Fig. 2, they will form a toggle joint. The end of the member vx is provided with 100 a shoulder va which is arranged to engage the heel H on the extension w of the counterweight W. Pivotally secured to the pin E by means of links L is a piston rod m of a piston M carried by the cylinder G. It will 105 be noted from an inspection of Fig. 2 that the toggle joint has a slight play at its center, a space such as that shown at e being left on one side or the other according as to whether the parts v and vx are in alignment or not. Springs U may be provided to normally hold the two members v and vx out of alignment. 110

From the foregoing description of the

various parts of the device, the operation thereof may be readily understood.

The normal position of the locking device is shown in Fig. 1. In this position, the bridge is open for traffic and the extension *w* of the counterweight *W* is firmly held against the bumper or abutment *Y*. When now it is desired to unlock the bridge so as to permit the counterweight *W* to enter the pit *Q* between the piers *P* and *P'*, the air on one side of the piston *M*, see Fig. 2, may be withdrawn and compressed air may be forced in the other side by any suitable means, thereby flexing the toggle joint in the manner shown in Fig. 2, and causing the shoulder *va* to leave the heel *H* so as to permit the bridge to be moved. The locking operation is precisely reverse of this for the piston *M* may be caused to drive the toggle joint forward, and when the shoulder *va* comes in contact with the heel *H* a further movement of the piston tends to straighten out the toggle joint and therefore to force the extension *w* into close contact with the bumper *Y*, thereby holding the bridge securely from movement. It will be seen that the toggle joint can be flexed only a short distance owing to the engagement of the semi-spherical bearing parts. It therefore cannot collapse, but is always in a position to be instantly applied or retracted. The lock is mounted under the approach of a bascule bridge, as shown where this form of lock is used.

In Figs. 4 and 5 I have shown a modified form of locking device which has certain common characteristics with that form already described, but which is designed to be operated in a different manner. In this form of the device, the anchor columns *S^a* and *S^b* on opposite sides of the roadway have secured to them locking members *V^a* and *V^b* of the type already described. Connected with the pivot pins *E* of each of these lock members are links such as that shown at *I^a*, these links in turn being connected to a guide block *K* arranged to travel on guides such as those shown at *X*. The block *K* is threaded to receive the threaded end of a rod *J* to which a gear *I* is secured. The latter is arranged to mesh with the gear *I'* on a shaft *J'* which extends to the operating house (not shown). Fig. 4 shows this form of locking means in its normal position, but in order to unlock the device it is only necessary to turn the shaft *J'* either manually or by power means when through the engagement of the gears *I* and *I'* the rod *J* will be revolved. This rod, as will be seen from Fig. 4, is provided at one end with a left-hand screw and at the other end with a right-hand screw, and it

will be understood that the blocks *K* are similarly provided with right and left-handed threads. The blocks will be simultaneously moved toward each other if the rod *J* is rotated in the direction shown by the curved arrow in Fig. 4, thereby flexing both of the toggle members and withdrawing them from the portions *H* of the bridge.

It will be seen that I have provided a simple device which will stand numerous strains but which may be easily moved so as to lock or unlock the bridge. If the parts become worn they can be readily replaced.

I claim:—

1. The combination with a lift or bascule bridge, of a locking device therefor, said locking device comprising a toggle joint, one end of said toggle joint being pivoted in a fixed position and the other end being arranged to engage a portion of the bridge.

2. The combination with a lift or bascule bridge, of a locking device therefor, said locking device comprising a toggle joint, one end of said toggle joint being pivoted in a fixed position, the other end being arranged to engage a portion of the bridge, and means for flexing the central portion of the toggle joint.

3. The combination with a lift or bascule bridge, of a pair of locking devices therefor, one on each side of the roadway, each of said devices comprising a toggle joint, one of the arms of the said toggle joint being pivotally attached to a fixed support, and the other arm being provided with a shoulder arranged to engage a portion of the bridge, means for flexing both of said toggle joints simultaneously, said means comprising a rod having a right-handed screw at one end and a left-handed screw at the other, a block arranged to be engaged by each of said screws, guide members for each of said blocks, and links connecting each of said blocks with the central portion of said toggle joint.

4. The combination with a lift or bascule bridge, of a locking device therefor comprising a toggle joint consisting of two arms pivotally connected together, each of said arms being provided with a shoulder arranged to engage a shoulder on the companion arm for limiting the pivotal movement of the joint, one of said arms being provided with a shoulder at its end arranged to receive a portion of the bridge, and the other of said arms being pivoted to a fixed support.
